ABSTRACT OF THE DISCLOSURE

An impact hammer with a periodically displaceable impact piston in which the impact piston is actuated by the stored energy of a spring which itself is stressed by movement of the piston in a direction opposite to the direction of the impact; the movement of the piston in the direction of stressing the spring is realized by frictional contact on the part of a piston actuating shaft with rollers of which at least one roller has a frictional surface over part of its circumference.

The present invention relates to an impact hammer, and more particularly to an impact hammer with a periodically actuated impact piston.

As high as possible an impact frequency is desirable with impact hammers. The prior art impact pistons driven either directly by a motor, by way of a connecting rod or by means of compressed air, do not permit in principle an increase in the impact frequency by reason of the inertia effect and of the elasticity of the actuating or driving compressed air. Furthermore, crank drives for the production of the impact movement have as a consequence vibrational forces by reason of the eccentric masses which are effective not only in the impact direction but also transversely with respect thereto which is very troublesome, disagreeable and fatiguing. They have their origin in the transverse components of the movement of the connecting rods. The accelerating and decelerating forces which occur thereby and which act horizontally cannot be compensated by simple means.

The present invention starts with the concept to limit movements to the longitudinal axis. In order to obtain simultaneously a strong impact action, the driving force does not act directly on the impact piston but at first on a spring which stores the impact energy, and which spring only accelerates the impact piston to its velocity required for the impact movement.

The present invention is concerned with an impact hammer having an impact piston periodically moved in the longitudinal axis under the effect of a spring. The drive takes place by a rotary motor.

The present invention essentially consists in that the impact piston is provided in its axial direction with a drive rod and a spring is arranged concentrically thereto pressing against the impact piston, and in that rollers arranged on both sides and symmetrically to the drive rod within roller bearings abut under pressure, whereby at least one of the rollers serves as driving roller, and this driving roller is provided over a part of its circumference with a friction surface with the shape of a body of rotation, and thus this frictional surface within its range is in frictional connection with the drive shaft, and thereby the other roller serves as counter-pressure roller, and in that the remaining part of the circumference of the driving roller has a smaller radius and is not in frictional connection within the area of the smaller radius with the drive shaft so that with a rotating drive roller, the impact piston is raised by the mutual frictional force within the circumferential area of the frictional connection and the spring is stressed thereby, and whereupon within the area in which no frictional connection

2

exists, the impact piston snaps back under the effect of the spring and carries out its impact work.

Accordingly, it is an object of the present invention to provide an impact hammer which is simple in construction, yet avoids the aforementioned shortcomings and drawbacks encountered in the prior art.

Another object of the present invention resides in an impact hammer with a periodically displaced impact piston that permits an increase in the impact frequency.

10 A further object of the present invention resides in an impact hammer of the type described above which minimizes vibrational forces and therewith minimizes compensating means.

These and further objects, features, and advantages 15 of the present invention will become more obvious from the following description when taken in connection with the accompanying drawing, which shows, for purposes of illustration only, two embodiments in accordance with the present invention, and wherein:

20 FIGURE 1 is a cross-sectional view through an impact hammer in accordance with the present invention showing the arrangement in principle thereof;

FIGURE 2 is a cross-sectional view through a modified embodiment of an impact hammer in accordance with 25 the present invention, representing an improved arrangement; and

FIGURE 3 is a cross-sectional view, taken along line A—A of FIGURE 2.

Referring now to the drawing wherein like reference 30 numerals are used throughout the various views to designate like parts, and more particularly to FIGURE 1, reference numeral 1 designates therein the housing which comprises the drive mechanism. A guide cylinder 2 is connected to the housing 1. The displaceable impact 35 piston 3 together with its impact surface 3a is disposed within the guide cylinder 2, axially guided along the interior walls thereof. The impact piston 3 carries out the periodic impacts against the impact tool 4 displaceably arranged axially below the impact surface 3a. The work tool may be, for example, a chisel that has a 40 collar 4a. The collar 4a is so guided within the walls 2a that it can carry out periodically and freely in the downward direction its impact force corresponding to the impact movement with a relatively short working 45 path. The impact body is under the counter-pressure of the storage spring 4 which rests against the housing 1. The return movement of the chisel after each impact takes place under the counter-pressure of the spring 12 and is limited by the wall 2a.

50 The piston 3 is provided in its axial direction with a drive rod or shaft 6. The force storage spring 5 is arranged

concentrically thereto and presses against the impact piston 3. Rollers 7 and 8 are present at the housing 1 and are arranged in ball bearings on both sides of the drive 55 shaft 6, as indicated, for example, by reference numeral 19 in FIGURE 2. In the illustrated position, the rollers 7 and 8 abut under pressure against the drive shaft 6. One roller 7 is provided in connection therewith over a part of its circumference with a cylindrical surface as friction surface 7a in the shape of a body of rotation. The roller 7 presses against the drive shaft 6 over the circumferential area of 7a whereas the roller 8, disposed opposite to roller 7 symmetrically and axially parallelly, presses against the drive roller 7 as counter-pressure roller. The

60 axes of the rollers 7 and 8 are disposed parallel in a plane perpendicular to the drive shaft 6. The friction surface 7a is thereby in frictional connection with the drive shaft 6 over a partial area of the circumference thereof. The remaining partial area 7b of the circumference of the roller 7 has a somewhat smaller radius. The transition 65 takes place at the leading edge 7c. The latter is slightly

70

rounded off in order to avoid an excessively abrupt transition.

Outside of the area of the surface 7a, a small gap thus exists between the drive shaft 6 and the drive roller 7. No frictional connection exists between the drive roller 7 and the drive shaft 6 within that part of the circumference. The roller 7 is simultaneously driving roller and is driven in a conventional manner by a motor by way of a gear transmission (not shown).

The operation is as follows:

When the motor has driven the driving roller 7 in the direction of the arrow, the friction surface 7a comes in pressure contact at its leading edge 7c with the friction surface of the drive shaft 6. As a result of the frictional force transmission resulting thereby, the drive rod 6 is seized during the further operation under clamping pressure and is thereby forcibly displaced upwardly together with the impact piston. The friction slippage still relatively large in the first stroke range, especially within the rounded-off area of the edge 7c, decreases very rapidly; the sliding friction passes over into a static friction or adhering friction that no longer slips. The drive rod 6 together with the impact body is torn along with great acceleration upwardly until after passage of the entire friction surface 7a, the latter again comes out of contact with the drive rod 6. Simultaneously, the spring 5 is compressed and thus the subsequent impact work stored until the frictional force transmission stops after passage of the friction surface. The movement of the impact body now reverses freely under the impact of the spring force, and the impact body is displaced downwardly with a large accelerational force by the spring 5 and strikes the chisel 4. During the further rotation of the now freely rotating drive roller 7, the leading edge 7c again reaches into pressure contact of the drive rod 6. The operation repeats itself. The counter-pressure roller 8 thereby carries out a corresponding rotation.

The arrangement according to FIGURE 1 offers the advantage of great simplicity. However, its output is limited. The latter can be increased in that the counter-pressure roller is also constructed as drive roller. For that purpose, the counter-pressure roller is connected with the first drive roller so as to rotate symmetrically thereto.

The rotational speed of the drive and therewith the number of impacts per second is limited by the time during which the impact body carries out its impact freely. The impact movement has to be ended before the leading edge 7c again comes into pressure contact with the friction surface. The larger the spring force of the spring, the smaller the impact time and the greater the impact frequency. The friction slippage is connected with an energy loss during the gliding friction. It can be kept small in that a small slippage path is achieved by a large abutment pressure of the driving roller.

FIGURES 2 and 3 illustrate such an arrangement which is more capable of greater outputs. In these two figures, reference numeral 1 again designates the housing having an installed driving motor 12 and a transmission 13. The guide cylinder 14 is arranged at the housing 1. The axially displaceable impact piston 3 is disposed within the housing 1 which carries out its impact movements by way of an intermediate piece 20 on the work tool 16, for example, a chisel, arranged therebelow and axially guided.

The drive rod 9 is provided with two mutually opposite parallel friction surfaces 9a and 9b. Driving rollers 17 and 18 are arranged on both sides and symmetrically with respect to the drive shaft 9 in roller bearings 19. The driving rollers 17 and 18 are coupled to each other rotationally symmetrically by way of gears 15 and 16. The driving rollers 17 and 18 are provided over a part of the circumference thereof with friction surfaces 17a and 18a disposed rotationally symmetrically to each other. The friction surfaces 17a and 18a are in frictional connection under high radial pressure with the parallel, mutually opposite friction surfaces 9a and 9b of the drive shaft 9.

The ball bearings disposed also symmetrically to the drive shaft 9 are radially so adjustable by any conventional means that the drive rollers press against the drive shaft 9 with the requisite friction pressure thereof. The friction surfaces are cylinder surfaces of equal radius; they extend with the same angle of rotation rotationally symmetrically to each other. Within the area of the remaining angle of rotation the drive rollers 17 and 18 have a somewhat smaller radius so that a gap results between the same and the drive shaft in which no frictional contact can occur. The leading edges 17c and 18c are rounded off in order to avoid an excessively abrupt entrainment of the drive shaft from the standstill. The pressure spring 5 is installed into the guide cylinder 14 which presses axially against the impact body. The impact body strikes at first against the sealing displaceably intermediate piece 20 only by means of which the impact takes place on the work tool 4. The one drive roller 17 is connected by way of the transmission gear 13 with the electric motor 12 built into the housing 1. With the arrangement according to FIGURES 2 and 3, the lifting of the drive rod takes place by way of two symmetrical and axially parallel cylindrical friction surfaces by means of two driving rollers which are driven rotationally symmetrically.

The best possible force transmission on the impact piston results therefrom. The impact piston 3 is provided with channels 3b disposed at its circumference by way of which a pressure equalization takes place between the upper and lower spaces of the guide cylinder.

While I have shown and described only two embodiments in accordance with the present invention, it is understood that the same is not limited thereto but is susceptible of numerous changes and modifications as known to a person skilled in the art. For example, the drive shaft instead of prismatic form with flat friction surfaces may also be constructed of cylindrical form. The driving rollers receive corresponding friction surfaces with cylindrical recesses.

Instead of the spring 5, an elastically effective air cushion may also be utilized whereby corresponding seals are necessary at the housing with respect to the drive shaft and the impact piston 3. The channels 3b then are obviated.

Thus, it is obvious that the present invention is not limited to the details shown and described herein, and I therefore do not wish to be limited thereto but intend to cover all such changes and modifications as are encompassed by the scope of the appended claims.

I claim:

1. An impact hammer and the like having an impact piston periodically movable in the direction of its longitudinal axis under the effect of spring means, and rotary motor means for driving said impact piston, wherein the improvement comprises a drive rod connected with the impact piston substantially in its axial direction, said spring means being disposed about said drive rod and normally resting on said impact piston, and roller means abutting against the drive rod under pressure on both sides thereof and at least approximately symmetrically thereto, one of said roller means forming a drive roller and being provided over a part of its circumference with a surface in the shape of a body of rotation, said surface being in frictional connection with the drive rod within its circumferential area so that with a rotating drive roller the impact piston is raised by the mutual frictional forces within the circumferential area of the friction connection and the spring means is stressed thereby whereupon the piston snaps back under the effect of the spring means within the area in which no frictional connection exists between the driving roller and the drive rod and carries out its impact work.

2. An impact hammer according to claim 1, further comprising ball bearing means for rotationally supporting said roller means on both sides of the drive shaft.

3. An impact hammer according to claim 2, wherein

the other roller means is also constructed as a drive roller and serves as counter pressure roller, and means operatively connecting said two roller means with said rotary motor means to rotate symmetrical to said one roller means.

4. An impact hammer according to claim 3, wherein said drive rod has the shape of a cylinder.

5. An impact hammer according to claim 3, wherein said drive rod has the shape of a prism.

6. An impact hammer according to claim 1, wherein the other roller means is also constructed as a drive roller and serves as counter pressure roller, and means operatively connecting said two roller means with said rotary motor means to rotate symmetrical to said one roller means.

7. An impact hammer according to claim 1, wherein said spring means is a compression spring.

8. An impact hammer according to claim 1, wherein said spring means is an air cushion adapted to be compressed.

9. An impact hammer and the like having an impact piston periodically movable in the direction of its longitudinal axis, comprising a drive rod operatively connected with the impact piston and disposed substantially in its axial direction, and means for imparting impact movement to said piston including elastic energy storage means stressed by movement of said piston in a direction opposite its impact direction, roller means abutting under pressure against the drive rod and disposed on both sides thereof at least approximately symmetrically thereto, at least one of said roller means forming a drive roller and being provided over a part of its circumference with a friction surface in the shape of a body of rotation, said

friction surface being in frictional connection with the drive rod within the circumferential area thereof, and drive means for at least said one roller means so that with a rotating drive roller means the impact piston is displaced by the frictional forces in the direction opposite the impact direction and the elastic means is stressed whereupon the piston snaps back under the effect of the elastic means within the circumferential area of the one roller means in which no frictional connection exists between the driving roller means and the drive rod.

10. An impact hammer according to claim 9, further comprising means for adjustably supporting at least said one roller means to adjust the contact pressure.

11. An impact hammer according to claim 9, wherein the two roller means are constructed as drive rollers, the other roller means serving as counter-pressure roller, and means operatively connecting said two roller means with said rotary motor means to rotate symmetrical to said one roller means.

12. An impact hammer according to claim 11, further comprising adjustable bearing means for adjustably supporting said two roller means to adjust the abutment pressure thereof with said drive rod.
